CLAIM

U.S. PATENT DOCUMENTS

The ornamental design for a probe for an ultrasonic diagnosis apparatus, as shown and described.

DESCRIPTION

FIG. 1 is a front, top and left side perspective view of a probe for an ultrasonic diagnosis apparatus, showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof; and,

FIG. 7 is a right side elevational view thereof.

It is certified that error appears in the above-identified patent and that said Letters Patent is hereby corrected as shown below:

The title page should be deleted and substitute therefor the attached title page

On the Cover Page, Section (30) Foreign Application Priority Data:
Please Insert --Aug. 11, 2005 (JP) 2005-023433--

On Pages 2-4, Figures 1-7:
Please replace the figures labeled 1-7 with the figures labeled 1-7 on the appended sheets

Signed and Sealed this

Twenty-third Day of September, 2008

JON W. DUDAS
Director of the United States Patent and Trademark Office
